(57) **CLAIM**

The ornamental design for a connection device for communication, as shown and described.

DESCRIPTION

FIG. 1 is a front, right side, top perspective view of a connection device for communication showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational thereof; and,

FIG. 7 is a rear elevational thereof.

The dashed broken lines in the drawings depict portions of the connection device for communication that form no part of the claimed design. The shade lines indicate the character and contour of the surfaces represented, and do not represent surface ornamentation or indicia.

1 Claim, 4 Drawing Sheets
